TENT CONSTRUCTION

Edward E. Ames, Atherton, Calif., assignor to Ames Harris Neville Co., San Francisco, Calif., a corporation of California

Application April 16, 1954, Serial No. 423,716

1 Claim. (Cl. 135—3)

This invention relates to a new and improved tent construction.

The present invention has particular reference to that class of tent structures which are frequently referred to as "pyramidal" tents. Tents of this category are characterized as comprising a generally pyramidal-shaped peak or roof portion supported centrally by a tent pole, and having a rectangular base stitched or otherwise attached to four depending walls, the line of juncture between the base of the roof portion and the walls being referred to hereinafter as the "eave line."

In the past, there have been proposed various ways for supporting and reinforcing pyramidal tents of the general type mentioned above. For example, so called "umbrella" type tents utilize a center pole in conjunction with a sleeve mounted slidably on the center pole carrying four pivotally mounted umbrella arms which, in turn, project toward and into engagement with the four corners of the tent for supporting the tent around its eave line. Although umbrella type tents provide certain advantages in rapidity and ease of tent erection, the umbrella arms which function to support the tent at its eave line also inherently restrict the available head room inside the tent. In short, even though the center peak or roof portion of the tent may extend upwardly substantially higher than the height of the eave line, the available head room inside of the tent is effectively restricted to the approximate height of the eave line by the substantially horizontal umbrella arms.

Another prior art method of supporting or reinforcing the eave line of pyramidal tents is to provide a series of exterior guy ropes extending from the eave line to anchoring stakes driven into the earth. Although the use of such guy ropes does not place a restriction upon the interior head room of the tent, this system of tent erection is both cumbersome and time consuming. Moreover, the use of guy ropes to reinforce the eave line in the manner above explained also results in the creation of an exterior rope barricade extending around the four sides of the tent which is not only unsightly, but constitutes an obstacle to pedestrian movement around the tent.

The particular embodiment of the present invention, which is illustrated in the drawings and which will be described hereinafter in greater detail, comprises essentially a rectangular frame positioned interiorly of the tent in contiguous reinforcing position around the eave line thereof. In the preferred embodiment, the frame comprises four lengths of wood fabricated and notched so that the frame pieces can be readily collapsibly assembled in such manner that they will function to maintain the rectangular eave line of the tent tautly distended and reinforced.

A novel feature of the invention is that in assembling the pieces into a frame structure inside the tent, the pieces can be manipulated in such way as to forcibly stretch the canvas material around the eave line to taut condition and to eliminate sag or slack in the material.

A principal object of the present invention, therefore, is to provide a pyramidal tent structure which incorporates unique interior eave line reinforcing means.

Another object of the invention is to provide in a pyramidal tent structure, a rectangular frame eave line reinforcing structure which permits unrestricted use of available head room within the tent and which does not require the use of exterior guy ropes or the like for reinforcing the eave line as found in certain prior art structures.

A more specific object of the invention is to provide a collapsible rectangular frame comprising four notched interfitting pieces which, when properly assembled, will function to provide interior reinforcement around the eave line of the tent and to maintain the tent material in tensioned or taut condition.

Another more specific object of the invention is to provide a novel rectilinear reinforcing frame of the character briefly mentioned above and which can be maintained in assembling the pieces together so as to cause the tent material to be stretched to taut condition around its eave line, with comparatively little human effort required.

Further objects of the invention will become apparent upon reading the following specification and referring to the accompanying drawings in which similar characters of reference represent corresponding parts in each of the several views.

In the drawings:

Fig. 1 is a perspective view of a tent embodying the invention showing portions thereof broken away in section.

Fig. 2 is a perspective view showing the component elements comprising the reinforcing frame in exploded relationship.

Fig. 3 is an enlarged fragmentary view of the roof portion and center pole.

Fig. 4 is an enlarged fragmentary view in perspective showing one of the anchoring stakes.

Fig. 5 is an enlarged fragmentary view in perspective showing a side frame member and its respectively associated receiving pocket in exploded relationship.

Fig. 6 is a top plan view of the tent construction with portions thereof shown broken away.

Referring now more particularly to the drawings, the tent structure therein illustrated is shown as comprising a generally pyramidal-shaped center peak or roof portion 10 having a rectangular base which, in turn, is stitched in conventional fashion to depending front, rear and side wall sections indicated at 11, 12, 13 and 14, respectively. The line of juncture between roof portion 10 and the wall sections 11-14 is indicated at 16 and will be referred to hereinafter as the "eave line" of the tent.

The tent structure is adapted to be supported in more or less conventional fashion by means of a center pole 17 having a pointed upper end 18 adapted to be projected in a reinforced opening or aperture 19 formed in the center of roof portion 10. The bottom edges of wall members 11-14 are shown as being provided with a rope-reinforced hem 21 to which stake rings 22 are secured, and through which conventional stakes 23 can be driven into the ground.

As indicated above, the present invention has particular reference to novel means for interiorly reinforcing the tent around its eave line 16. Referring particularly to Fig. 2, there is disclosed a rectangular reinforcing frame, indicated generally at 24, in conjunction with four frame member receiving pockets indicated at 26^a, 26^b, 26^c and 26^d. The frame structure 24 in its preferred embodiment comprises more specifically a pair of substantially identically formed parallel side members 27 and 28 and a pair

of parallel end members 29 and 31, respectively. Frame members 27 and 28 are shown as each comprising a solid straight wood piece, the inner surface of which is formed with a pair of transverse grooves located adjacent the end extremities of each piece and indicated at 32^a—32^b and 33^a—33^b in the drawings. End pieces 29 and 31 may similarly comprise straight wood pieces, each being formed with end cut-outs or notches as indicated at 34^a—34^b and 36^a—36^b. Preferably, the stock out of which end pieces 29 and 31 are formed is substantially thicker than the stock out of which side pieces 27 and 28 are made so that the channel-shaped end notches in pieces 29 and 31 can be made large enough to receive and embrace pieces 27 and 28 in a manner to be described hereinafter. As will more fully hereinafter appear in assembly, the end notches formed in end pieces 29 and 31 are adapted to engage within the transverse grooves formed in side pieces 27 and 28 to prevent displacement of the frame members when properly positioned to reinforce the eave line of the tent.

The frame member receiving pockets 26 may be formed of heavy canvas or similar fabric material which can be readily stitched to the fabric of the tent structure itself. It is observed that the openings in oppositely disposed corner pockets extend toward one another to receive opposite end extremities of the side frame pieces 27 and 28.

In erecting a tent structure embodying the present invention, it is desirable to first stake out the base of the tent in conventional fashion utilizing stake rings 22 in conjunction with conventional stakes 23. After the base has been anchored, the center pole 17 may be inserted through the roof aperture 19 and the pole moved to its upright supporting position centrally of the tent. Raising of the pole to its upright position shown in the drawings will, of course, elevate the entire tent structure off the ground and raise the center peak of roof portion 10 to its maximum height. In this latter condition of assembly, the roof portion 10 including the eave line 16 will be unreinforced and will therefore drape or sag downwardly around the tent pole.

To insert the reinforcing frame 24 around the eave line, an operator, working from the inside of the tent, will first insert the end extremities of side frame piece 27 in pockets 26^a and 26^b and the end extremities of side piece 28 within pockets 26^c and 26^d. The end pieces 29 and 31 may then be positioned and engaged one at a time with the side pieces. Thus, for example, notch 34^a of end piece 29 may be initially interfitted with transverse groove 32^b formed in side piece 27. Thereupon, end notch 34^b of piece 29 can be engaged with side piece 28 at any point along the length of side piece and slidably moved along the length of said side piece until notch 34^b engages within transverse groove 33^b.

Positioning of end piece 31 may then be accomplished in substantially the identical manner described with respect to end piece 29. More specifically and by way of example, end notch 36^b of piece 31 may be initially engaged within transverse groove 33^a of side piece 28. Thence, end notch 36^a of end piece 31 may be manipu-

lated to engage and embrace side piece 27 at any point along its length between notches 32^a and 32^b. With end notch 36^a embracing side piece 27, the former may be moved slidably forcefully along the length of the side piece into engagement with transverse groove 32^a, whereupon the assembly of the pieces into a rectangular reinforcing frame is complete.

A novel feature and advantage of the invention resides in the ability of an operator to cause the canvas or treated cloth material defining the eave line of the tent to stretch to taut condition during assembly of the frame pieces to one another inside the tent and in the manner above described. In particular and as above noted, by first engaging one notched end of each end piece with an associated groove of a side piece and then forcefully sliding the second notched end of the end piece along the second side piece, the latter is, in effect, forcefully cammed outwardly to spread position, consequently causing the tent material to stretch to taut condition.

As indicated earlier, another advantageous feature of the invention is that the rectangular frame for reinforcing the eave line of the tent does not restrict or interfere with the available head room inside the tent.

Although the present invention has been described in some detail by way of illustration and example, it is understood that certain changes and modifications may be made within the spirit of the invention as limited only by the scope of the claim appended hereto.

I claim:

In a tent structure of the type incorporating a generally pyramidal-shaped roof portion supported by a center pole and a rectangular frame joined to depending wall members; and a rectangular frame reinforcing the interior periphery of the walls to define a rectangular eave line; the combination of said frame having a pair of spaced, parallel side pieces, and a pair of spaced, parallel end pieces; the inner lengthwise surface of each side piece formed with a pair of transverse grooves adjacent the end extremities of said piece; each end of each end piece formed with a channel-shaped notch proportioned to slidably embrace the body portion of an associated side piece and to engage within an associated groove of said side piece, whereby in assembly the first notched end of each end piece may be engaged in an associated groove of a first side piece and the second notched end of each end piece may be slidably engaged with the central body portion of a second side piece and forcibly slidably moved lengthwise of said second side piece toward and into engagement with an associated transverse groove thereof to cause the tent material to be stretched tautly at its eave line.
